UNITED STATES PATENT OFFICE.

MOSES C. JOHNSON, OF HARTFORD, CONNECTICUT, ASSIGNOR TO THE HELIX GEAR COMPANY, OF SAME PLACE.

DESIGN FOR A GEARING-COVER FOR VEHICLE-FRAMES.

SPECIFICATION forming part of Design No. 31,325, dated August 1, 1899.

Application filed July 5, 1899. Serial No. 722,882. Term of patent 14 years.

To all whom it may concern:

Be it known that I, MOSES C. JOHNSON, a citizen of the United States, and a resident of Hartford, in the county of Hartford and State of Connecticut, have invented a new and original Design for a Gearing-Cover for Vehicle-Frames; and I do hereby declare the following, when taken in connection with the accompanying drawings, to be a full, clear, and exact description of the same, and said drawings constitute part of this specification, and represent, in—

Figure 1, a view in side elevation of a gearing-cover embodying my design; Fig. 2, a view in front elevation of the same, and Fig. 3 a view in rear elevation of the gearing-cover.

My invention relates to a design for a gearing-cover for a bicycle or the like which as a whole is especially adapted as an article of manufacture to be connected to or form part of the frame of a bicycle or like vehicle. This gearing-cover, when used as described, comprises a casing for the crank-shaft, connecting-shaft, and also for the gearing at the crank-hanger and at the rear end of the bicycle-frame; and my invention consists in the configuration of the structure, as hereinafter described and shown in the drawings.

The structure as a whole comprises a circular part *a*, as viewed in side elevation, a circular part *b* of smaller diameter, and an elongated central portion *c*, extending from be-

low the part *b* to a point above the part *a*. The part *c* terminates at each end in enlargements *d* and *e* of cylindrical form in outline and having walls which merge into the walls of the parts *a* and *b*, respectively. 35

When viewed in front elevation, as in Fig. 2, the part *a* appears as cylindrical in outline, with a portion *a'* of smaller diameter than 40 the circular portion *a*, above which the circular end of the part *d* appears.

When viewed in rear elevation, the oblong outline of the short cylindrical part *b* appears above the circular outline of the end of the 45 part *e*, the walls of these two parts merging into each other.

The essential feature of my design is the arrangement of the gear-covers *a b*, the former larger in diameter than the latter, with 50 the connecting parts *d c e* extending diagonally across between the parts *a* and *b*, the part *d* overlying the part *a*, and the part *e* underlying the part *b*.

I claim—

The design for a gearing-cover for vehicle-frames substantially as shown and described.

In witness whereof I have signed this specification in the presence of two subscribing witnesses.

MOSES C. JOHNSON.
